UNITED STATES PATENT OFFICE

159,908

MEAT TENDERIZER OR SIMILAR ARTICLE

Edward M. Hulquist, Dallas, Tex.

Application June 13, 1949, Serial No. 3,234

Term of patent 3½ years

(Cl. D44—29)

To all whom it may concern:

Be it known that I, Edward M. Hulquist, a citizen of the United States, residing at Dallas, in the county of Dallas and State of Texas, have invented a new, original, and ornamental Design for Meat Tenderizer or Similar Article, of which the following is a specification, reference being had to the accompanying drawing, forming part thereof.

Figure 4 is a front elevational view of a meat tenderizer or similar article, showing my new design.

I claim:

The ornamental design for a meat tenderizer or similar article, substantially as shown.

EDWARD M. HULQUIST.
